UNITED STATES PATENT OFFICE.

PERLEY A. GERRY, OF LAWRENCE, MASSACHUSETTS.

COMBINATION-TOOL HOLDER.

SPECIFICATION forming part of Letters Patent No. 393,698, dated November 27, 1888.

Application filed May 23, 1888. Serial No. 274,830. (No model.)

to all whom it may concern:

Be it known that I, PERLEY A. GERRY, a citizen of the United States, residing at Lawrence, in the county of Essex and State of Massachusetts, have invented a new and useful 5 Combination-Tool Holder, of which the following is a specification.

My invention relates to improvements in that class of hand implements embodying a 10 ratchet and pawls operative through a reciprocating lever, the object of my improvement being to provide an instrument which may be immediately convertible into manifold uses through its interchangeable construction and 15 especially adapted to the various uses of a reamer, center-bit, bolt-wrench, drill-holder, screw-driver, &c., as severally illustrated in the annexed drawings, forming a part of this specification, wherein—

20 Figure 1 is a linear perspective of my combination-tool holder separably attached to a bolt-wrench consisting of the ordinary sliding jaws controlled by a right-and-left threaded adjusting-screw. Fig. 2 exhibits a like perspective, a part broken away, the stock secured in the handle and sustaining a drill with an auxiliary support indicated in dotted lines. Fig. 3 is a view with the stock attached, its geared head, with the actuating-lever 25 pawls appearing in dotted lines, and a center-bit inserted in the stock. Fig. 4 indicates a perspective view of the retracting-collet. Fig. 5 designates the retaining-plate, with the supporting-screw in dotted lines. Fig. 6 exhibits 30 its a perspective of the tool-holder, the retaining-plate removed to show the position of the lever-pawls, the right engaging with the ratchet-head of the stock, which in this view sustains a reamer. Fig. 7 delineates in perspective a half-section transversely vertical of 35 said tool-holder, the retaining-plate removed to better display the recesses confining the lever-pawls, (one of the latter removed therefrom,) and the helical springs actuating said 40 pawls seated in their respective positions; and Fig. 8, a transverse vertical central section 45 through said tool-holder and the bolt-wrench as would appear on the dotted line 22, Fig. 1, in the assemblage of these parts.

50 The function of the various parts, with their construction and relation, will be fully comprehended by referring to the drawings, in which—

A indicates the tool-holder proper, and B the retaining-plate thereon secured by the screws C. The interior of said holder is circularly chambered, as at D, Fig. 7, to receive the stock holding the various implements before mentioned used in connection therewith and which are actuated through the medium of right-and-left rock-lever pawls E E, as they 55 are caused to engage with the geared head F of the various stocks G, of which there may be diverse patterns applicable to various tools and uses, as previously mentioned. Said rock-lever pawls E E are seated within depressions 60 H H, conforming to such a degree with said lever-pawls as to admit a slight oscillatory motion to them, imparted by right-and-left helical springs I I, seated within circular recesses J J and expanding against the rear 65 arms of these lever-pawls, while otherwise, in conjunction with said retaining-plate B, they are confined to the part A, as exhibited in Fig. 3. The peculiar construction of said depressions, with that of the lever-pawls, obviates the use of pivotal bearings, the projections K K', in the assemblage of the parts, lying in juxtaposition, so that the former, K, 70 acts as the fulcra for the latter, K'. It will be observed that said depressions H H extend 75 downward from the plane of the offset L, Fig. 7, contiguous to the lower plane, M, of the plate B, Fig. 5, when the parts are united.

In the manipulation of the rock-lever pawls I provide a retracting milled collet, (designated as N, Fig. 4,) which surrounds the neck O of the tool adjacent to the handle P, and on which it is rotated by manual pressure to circumscribe the motion alternately or simultaneously of the arms E' E'. I accomplish this 85 by forming within the overlapping rim Q, which covers the rear portion of said rock-lever pawls, two re-entering slots, R R, double the width of the pawl-arms E' E', with which they coact, that one may be confined while the 90 one opposite may be unconfined, or that both may be liberated, if desired. An additional mortise, S, upon the edge remote from the rim Q serves in conjunction with a stop or stud, T, projecting from the elongated neck B' of said 95 retaining-plate, to limit the rotation of said 100 collet.

U indicates my improved tang, over which the handle P, of any suitable material, if not

integral with the holder, may be confined by the usual nut and thread, as at V. In the manufacture of my combination tool holder I may find it incumbent to modify in some degree without departing from the spirit of my invention the method of confining my stock G thereto, as exemplified in the supporting-screw W, Figs. 2 and 5. To obviate any tendency said screw may have to bind the stock to the tool-holder, thereby impeding its free rotation, I construct the externally-threaded supporting-screw of sufficient length that when firmly seated in the internally-threaded geared head of the stock the shoulder of the screw will project slightly above and over the retaining-plate B, so as to support the same and to avoid friction of the parts, offering no resistance to the proper manipulation of the tool designed for the use of heavy implements in contradistinction to the light nut and thread X, forming an integral part of said socket, as exhibited in section, Fig. 8. In a like manner a modification of my stock might occur, as between Figs. 2 and 8, the former being adjustable to multiform diameters of augers, center-bits, &c., the shanks of which would ordinarily suit one stock, while the latter would be more convenient if united to the adjustable implement therein illustrated.

The practical operation of my invention I will briefly describe, assuming the employment of the drill, as in Fig. 2, the chamber D being empty, as observed in Fig. 7, but otherwise organized for the work it is to perform. The operator then thrusts the geared head F of the stock G into said chamber D, compressing meanwhile the arms E' of the loose lever-pawls E inwardly, that their working ends may offer no obstruction to the free ingress of the stock, which latter is then secured by the supporting-screw W, (or in the use of the lighter instruments the nut X,) while the lever-pawls engage with said head F. Should it be desired to operate the drill to the right, then the arm E' is confined by the partial rotation of the retractor N, as in Fig. 6, the expansion-spring I, Fig. 7, forcing outward the arm E', thus engaging the working end or nose of the lever-pawl E to actuate said drill through the reciprocating movement of the handle. The reverse order of this arrangement obviously rotates the drill to the left.

I am aware that duplex pivoted pawls and ratchets are unitedly in common use—for example, in ratchet-wrenches, as exemplified in the United States Patent No. 335,481, dated February 2, 1886. I am further aware that pawl-retractors of a segmental construction are used on implements of the kind mentioned, as evidenced in the United States Patent No. 343,628, of date June 15, 1886, as also the use of non-removable stock in similar applications, notably United States Patent No. 52,962, October 13, 1868. I therefore do not claim such features, broadly; but

What I desire to secure by Letters Patent, and claim, is—

1. A combination-tool receptacle consisting of the following elements: a "tang" constructed with a circular head, A, provided with a vertical receiving-chamber, D, the upper plane of the side walls thereof being provided with depressions H H, substantially as shown, the pivotless rocker-pawls E E, constructed to be therein adjusted, and further provided integrally upon their inner faces with projections K' K', designed to abut against similar projections, K K, forming a part of said depressions, to permit said pawls to be depressed, the helical springs I I, actuating said pawls, the retractor N, provided with duplex re-entering slots R R, adapted to confine or release said pawls, and a re-entering mortise, S, to restrict its rotation, the internally-threaded stock G, provided with a geared periphery, F, adapted to coact with said pawls, and a conical recess to receive the various implements to be used therewith, all constructed and assembled to operate substantially as specified.

2. In a combination-tool receptacle, a tang, U, provided with a semicircular offset, L, terminating in a vertical circular chamber, D, the duplex depressions H H in the side walls thereof, the projections K K, forming an element of said depressions, and the recesses J, arranged and constructed to operate in combination with an interchangeable tool stock, G, having a geared head, F, integral therewith, provided at its upper end with a threaded cavity longitudinally for its support to said tang and at its lower end with a converging cavity to receive the cutting-tool, the screw W, supporting said stock, the pivotless lever-pawls E E, provided with shoulders K' K', the means, substantially as described, whereby they receive an oscillatory motion, the retracting-collet N, and the retaining-plate B, provided with a stud, T, to restrict the rotation of said collet, in the manner and for the purpose set forth.

3. In combination with a tang, substantially as described, the retaining-plate B, provided with an elongated neck, B', upholding a stud, T, and further provided with a central perforation for the admission of a supporting-screw, W, the retractor N, provided with duplex re-entering slots R R on opposite sides of its periphery adjacent to said lever-pawls, and a re-entering mortise, S, within the rear periphery, the pivotless rock-lever pawls E E, geared stock G, and springs I I, as and for the purpose specified.

In testimony whereof I have signed my name to this specification, in the presence of two subscribing witnesses, on this 19th day of May, A. D. 1888.

PERLEY A. GERRY.
